UNITED STATES PATENT OFFICE.

JONAS W. AYLSWORTH, OF EAST ORANGE, NEW JERSEY, ASSIGNOR, BY MESNE ASSIGNMENTS, TO PYRENE MANUFACTURING COMPANY, A CORPORATION OF DELAWARE.

FIRE-EXTINGUISHING LIQUID.

1,154,161.

Specification of Letters Patent. Patented Sept. 21, 1915.

No Drawing.

Application filed May 25, 1909. Serial No. 498,358.

To all whom it may concern:

Be it known that I, JONAS W. AYLSWORTH, a citizen of the United States, and a resident of East Orange, in the county of 5 Essex and State of New Jersey, have made a certain new and useful Invention in Fire-Extinguishing Liquid, of which the following is a description.

This invention relates to a liquid composition suitable for extinguishing fire, and 10 one of the objects of my invention is to produce an efficient agent of this character, the characteristics of which will be described in the following specification and particularly 15 pointed out in the appended claims.

My invention consists also in an improved process for extinguishing fires.

It has long been known that carbon tetra-chlorid is an excellent liquid for extinguishing flames. This substance, however, has 20 one very objectionable feature as a fire extinguisher which very materially decreases its efficiency for such purposes. This is the volatility of the substance when heated, the 25 point at which carbon tetra-chlorid volatilizes being so low that when it is used to extinguish a fire which is well under way, the carbon tetra-chlorid is expelled instantly by the heat and the flames burst out afresh, 30 making it necessary to use far greater quantities of this substance than would be necessary if its boiling point were higher. I find that this difficulty is overcome by dissolving in the carbon tetra-chlorid a substance having 35 a much higher boiling point than that of the carbon tetra-chlorid and serving to retard the rate of volatilization of the latter. Such substances are perhalogenized organic 40 radicals such as perchlorinated naphthalene and di-phenyl, hexa-chloro-ethane, per-chloro-triphenyl-benzene, hexa-chloro-benzene, etc. These substances have fire extinguishing properties and serve to augment as well as prolong the fire extinguishing effect 45 of the carbon tetra-chlorid. They are also electrically non-conducting. In the term "perhalogenized organic radicals" mentioned above, I do not mean to limit myself to substances in which all the hydrogen has 50 been replaced by chlorin or other halogen, but only to substances in which the greater part of the hydrogen has been so replaced. While chlorin is the least expensive and the 55 most suitable halogen to use, other halogens, such as bromin, may be used with good re-

sults. By mixing any of the above named or equivalent substances with the carbon tetra-chlorid, a liquid is obtained which will continue to evolve flame extinguishing vapors at all ranges of temperature from the 60 boiling point of carbon tetra-chlorid up to and over 600 degrees F.

My improved fire extinguishing liquid is substantially devoid of water and is electrically non-conducting. It has its resistance 65 increased by the presence of the electrically non-conducting ingredient or constituent consisting of any of the perhalogenized organic radicals mentioned above. In the use of the liquid in extinguishing fires, some of 70 the perhalogenized organic constituent is thrown down on the burnt material as an electrically non-conducting deposit. This feature is of advantage in extinguishing certain classes of fires, as for example, where 75 an electric arc is formed. In the practice of my invention in extinguishing fires, the liquid compound is thrown upon the fire to be extinguished and thereby there is liberated a thick, heavy, homogeneous, penetrating, cohering, lingering, blanket of dry 80 gas and vapor which covers closely and extinguishes the fire. At the same time an electrically non-conducting deposit is thrown down upon the burned material rendering it 85 electrically non-conducting. The comparatively heavy gaseous mantle composed of carbon tetra-chlorid and vapors of the halogenized substances associated therewith is 90 not carried off rapidly by the products of combustion but holds together in a dense cloud for a period of appreciable and effective length, enveloping the seat of combustion, shutting off access of air and sinking 95 into the interstices of the burned material, if any interstices be present. The property of the gaseous blanket whereby it preserves its integrity, together with its activity in penetrating the burning material, enables the extinguishing liquid both to effectually 100 smother a blaze and to extinguish thoroughly any subsequent smolder. When applied to burning liquids, the compound does not scatter these liquids, still burning, without extinguishing them, but at once vaporizes, producing the enveloping and smothering 105 blanket alluded to.

An especially advantageous feature of the present invention is found in the fact that the compound hereinbefore described when 110

volatilized by the heat produces a blanket composed of non-poisonous elements, thus rendering the compound commercially practical and capable of being freely used without danger of asphyxiation of the operator.

By my improved process, I am enabled to extinguish fires by establishing over the burning material or seat of combustion a heavy, homogeneous, cohering, lingering 10 blanket of dry, combustion-arresting gas, and at the same time to reduce electrical conductivity by the presence in the liquid compound of an electrically non-conducting ingredient, which increases the resistance of 15 the liquid and is thrown down as a resistance deposit on the burned material when the compound is volatilized by heat.

The liquid may still further be improved for certain purposes by adding thereto certain metallic salts which will serve to coat the charred carbon after all volatile matter is expelled therefrom and retard its burning. Such salts as finely divided tungstate 20 of soda mechanically mixed with the liquid 25 may be used.

As an example of a composition made in accordance with my invention and having proportions which give excellent results, I give the following:—Carbon tetra chlorid, 30 100 parts by weight; chlorinated organic radical, such as perchlorinated naphthalene, that is, tetra-chlor-naphthalene or chloro-naphthalene of higher proportions of chlorin, 2 to 20 parts by weight; perhalogenized benzene, toluene or ethane might be used as equivalents of the per-chlor-naphthalene. Or the above composition might be used together with a fine powdered mineral fire-proofing substance held in suspension, such as tungstate of soda, bicarbonate 40 of soda, phosphate of soda or phosphate of ammonia, 5 to 20 parts by weight.

Having now described my invention, what I claim and desire to protect by Letters Patent is as follows:

1. A fire-extinguishing liquid consisting of carbon tetra-chlorid having dissolved therein a halogenized aromatic hydrocarbon having a boiling point much higher than 50 that of the carbon tetra-chlorid, substantially as described.

2. A fire-extinguishing liquid consisting of carbon tetra-chlorid having dissolved therein a halogenized substitution benzene 55 derivative having a boiling point much higher than that of the carbon tetra-chlorid, substantially as described.

3. A fire-extinguishing liquid consisting of carbon tetra-chlorid having dissolved 60 therein a perchlorinated organic radical having a boiling point much higher than that of the carbon tetra-chlorid, substantially as described.

4. A fire-extinguishing liquid consisting 65 of carbon tetra-chlorid having dissolved

therein a substance having a boiling point much higher than that of the carbon tetra-chlorid and serving to retard the rate of volatilization of the latter, and having mixed therewith a metallic salt adapted to 70 coat the charred carbon of the substance burned after all volatile matter is expelled and retard its burning, substantially as described.

5. A fire-extinguishing liquid consisting 75 of carbon tetra-chlorid having dissolved therein a substance having a boiling point much higher than that of the carbon tetra-chlorid and serving to retard the rate of volatilization of the latter, and having 80 mixed therewith finely divided sodium tungstate, substantially as described.

6. A fire-extinguishing liquid consisting of carbon tetra-chlorid having dissolved 85 therein a halogenized substitution benzene derivative having a boiling point much higher than that of the carbon tetra-chlorid, and having mixed therewith finely divided sodium tungstate, substantially as described.

7. A fire extinguishing liquid consisting 90 of carbon tetra-chlorid having dissolved therein a substance having a higher boiling point than that of the carbon tetra-chlorid and having flame extinguishing properties, and having mixed therewith a metallic salt 95 adapted to coat the charred carbon of the substance burned after all volatile matter is expelled and retard its burning, substantially as described.

8. A fire extinguishing liquid consisting 100 of carbon tetra-chlorid having dissolved therein a substance having a higher boiling point than that of the carbon tetra-chlorid and having flame extinguishing properties, and having mixed therewith finely divided sodium tungstate, substantially as described. 105

9. A fire extinguishing liquid containing carbon tetra-chlorid having dissolved there- 110 in a halogen derivative of naphthalene, substantially as described.

10. A fire extinguishing liquid containing carbon tetra-chlorid having dissolved there- 115 in a chlorin derivative of naphthalene, substantially as described.

11. A fire extinguishing compound con- 120 sisting of a liquid which, when heated by being applied to the seat of combustion, in part volatilizes to produce a lingering blanket of dry, combustion-arresting gas, and in part is thrown down as an electrically non-conducting deposit, substantially as described.

12. A fire extinguishing compound com- 125 prising carbon tetra-chlorid and a constituent which is thrown down when the compound is heated by being applied to a fire as an electrically non-conducting deposit, substantially as described.

13. A fire extinguishing compound, com- 130

prising a liquid substantially devoid of water adapted and capable of being volatilized by the heat of the fire and producing a heavy lingering cohering and homogeneous 5 blanket of dry combustion-arresting gas, substantially as described.

14. A fire extinguishing compound, comprising a liquid substantially devoid of water adapted and capable of being volatilized 10 by the heat of the fire and producing a lingering penetrating cohering and homogeneous blanket of dry combustion-arresting gas, substantially as described.

15. A fire extinguishing compound, comprising a liquid substantially devoid of water adapted and capable of being volatilized by the heat of the fire and producing a lingering cohering blanket of dry combustion-arresting gas and an electrically non- 20 conducting deposit, substantially as described.

16. A fire extinguishing compound, comprising an electrically non-conducting liquid adapted and capable of being volatilized by 25 the heat of the fire and producing a lingering cohering blanket of dry combustion-arresting gas and an electrically non-conducting deposit, substantially as described.

17. A fire extinguishing compound, comprising a liquid substantially devoid of water adapted and capable of being volatilized by the heat of the fire to produce a heavy 30 non-poisonous, cohering and homogeneous blanket of combustion-arresting, non-inflammable 35 gas, substantially as described.

18. The process of extinguishing fires which consists in establishing at the seat of combustion a lingering, cohering blanket of dry, combustion-arresting gas, and simultaneously 40 causing an electrically non-conducting deposit to be thrown down, substantially as described.

19. The process of extinguishing fires which consists in establishing at the seat of combustion a lingering cohering and homogeneous blanket of dry, combustion-arresting non-poisonous gas, by throwing on the 45 fire a liquid substantially devoid of water and capable of being volatilized by the fire 50 to produce such gaseous blanket, substantially as described.

20. The process of extinguishing fires which consists in causing the burning material to be enveloped with a lingering, cohering and homogeneous blanket of dry gas 55 which also penetrates the burning mass, by applying a liquid in such a manner that the heat of the fire causes the same to be volatilized and to produce such gaseous blanket, 60 substantially as described.

21. The process of extinguishing fires which consists in enveloping the burning

material with a lingering, cohering blanket of dry, combustion-arresting gas, inherently penetrative of the burning materials, substantially as described. 65

22. A fire extinguishing compound comprising a non-inflammable solvent, a non-inflammable compound dissolved therein having more carbon atoms in its molecule 70 than the solvent, said dissolved compound containing a halogen in its molecule.

23. A fire extinguishing compound comprising a non-inflammable solvent, a non-inflammable compound dissolved therein 75 having a higher boiling point than the solvent, and containing a halogen in its molecule.

24. A fire extinguishing compound comprising a non-inflammable solvent, a non-inflammable compound dissolved therein 80 having more carbon atoms in its molecule than the solvent and having a higher boiling point than the solvent, and also containing a halogen in its molecule. 85

25. A fire extinguishing compound comprising a non-inflammable solvent, a non-inflammable compound dissolved therein having a higher boiling point than the solvent, and containing chlorin in its molecule. 90

26. A fire extinguishing compound comprising a non-inflammable solvent, a non-inflammable compound dissolved therein having more carbon atoms in its molecule 95 than the solvent, and also containing chlorin in its molecule.

27. A fire extinguishing compound comprising a non-inflammable solvent, a non-inflammable compound dissolved therein 100 having more carbon atoms in its molecule than the solvent and having a higher boiling point than the solvent, and also containing chlorin in its molecule.

28. A fire extinguishing compound comprising carbon tetrachlorid in which is dissolved a non-inflammable carbon compound containing a halogen in its molecule, and with more than one carbon atom in its molecule. 105

29. A fire extinguishing compound comprising carbon tetrachlorid in which is dissolved a non-inflammable carbon compound containing a halogen in its molecule, with more than one carbon atom in its molecule, 115 and a boiling point higher than carbon tetrachlorid.

This specification signed and witnessed this 22nd day of May 1909.
